At the

UNITED STATES PATENT OFFICE.

WILLIAM SCHWEITZER AND HARRY H. LABADIE, OF CHICAGO, ILLINOIS; HARRY H. LABADIE ADMINISTRATOR OF SAID SCHWEITZER, DECEASED.

PORTABLE AND COLLAPSIBLE TABLE FOR AUTOMOBILES.

1,129,609.

Specification of Letters Patent. Patented Feb. 23, 1915.

Application filed July 21, 1913. Serial No. 780,221.

To all whom it may concern:

Be it known that we, WILLIAM SCHWEITZER and HARRY H. LABADIE, citizens of the United States, and residents of the city of 5 Chicago, in the county of Cook and State of Illinois, have jointly invented certain new and useful Improvements in Portable and Collapsible Tables for Automobiles; and we do hereby declare that the following 10 description of our said invention, taken in connection with the accompanying sheets of drawings, form a full, clear, and exact specification, which will enable others skilled in the art to which our said invention appertains to make and use the same.

This invention has general reference to improvements in portable and collapsible tables for automobiles, and it consists, essentially, in the novel and peculiar combination 20 of parts and details of construction, as hereinafter first fully set forth and described, and then pointed out in the claims.

In the drawings already referred to, which serve to illustrate our said invention more 25 fully, Figure 1 is a perspective view of a portion of a touring car body with our collapsible table installed therein. Fig. 2 is a transverse section of a fragment of our device. Fig. 3 is a section in line 3—3 of Fig. 30 2. Fig. 4 is a like section of a modified form of detail of construction taken as in line 4—4 of Fig. 2. Figs. 5 and 6 are perspective views of essentially similar devices for maintaining a luncheon case, forming the 35 table member of the invention, in connection with the supporting means therefor. Fig. 7 is a section of a fragment in line 7—7 of Fig. 2.

Like parts are designated by corresponding 40 characters or symbols of reference in all the figures of the drawings.

It is one aim of our invention to provide for the use of touring motorists a convenient, collapsible, and portable luncheon carrier and table which is supported from the 45 floor of an automobile and caused to forcibly rest against the rear of the front seat thereof to impart an ample degree of steadiness to said table.

Another aim is to combine with said table, 50 a preferably rectangular case, of which the table top proper is the cover, within which case are provided outwardly movable trays; to one of which trays said cover is hinged. 55 The said trays are adapted for the reception

of eatables of various kinds, and may possess compartments to prevent the mixing together of the variety of foodstuffs contained therein. They do not occupy the entire interior of the case, there being room beyond both ends thereof and the case end walls, and between the trays and back of the case for bottles and flasks of various descriptions, and also for the necessary dishes required. The luncheon case element of our 60 invention has been separated from this application and filed as a divisional application May 11, 1914, Serial No. 837,196, and the essence of this parent application is the provision of simple devices to support the 65 said case in position within the car and to facilitate its removal therefrom. In view of the fact that there is a great divergence in the details of design and measurement of the bodies of the various makes of touring 70 cars, the supports for said case are provided with sufficient adjustments to render the 75 same practically applicable to any automobile without change or modification. The aforesaid divergence resides mainly in the 80 rearward slope of the back of the front seat and the height of said back. We have, therefore, (after securing the required information from the makers of all standard cars) designed our invention so that the 85 normal of these divergences will be the normal adjustment of the said supports, and the mean and extreme referred to above, the mean and extreme adjustability of our device.

Reference is now made to the drawings in which—

A indicates a portion of an automobile in perspective; R and F the rear and front seats, respectively, and F' the rear wall of 95 the said front seat F; B being the luncheon case disclosed and claimed in the hereinbefore indicated divisional application, and hereinafter referred to generally as the table member B. Soft rubber buttons 10 are af- 100 fixed to this member at points where the same are intended to contact with the rear wall F' of the automobile seat F to afford a resiliency of contact preventive of vibration of parts while the automobile is in 105 motion.

Fastened to the floor of the automobile by through bolts 85 are a pair of floor bases S, located parallel to the seat back F', a proper distance apart. Said floor bases are each 110

possessed of an upstanding hub 60, internally bored to freely receive a vertical standard or post 61 and provided with slotted lugs 62 at its upper end. Through said lugs is passed a bolt 63 provided with a thumb nut 64, whereby the post 61 may be firmly clamped in position.

At the upper end of each of the standards or posts 61 is firmly brazed or otherwise attached a sleeve 65 having upwardly and outwardly projecting hinge lugs 66 and 67 and a pintle 68. Embracing said pintle between said hinge lugs is a hinge lip 69 depending from a flat oscillable metallic blade 70. On each of the said posts or standards 61, adjacent the upper end of the hubs 60, there is freely mounted a sleeve 74 having ears 75, between which ears is retained a rod 100 by means of a bolt and thumb nut 77; and, pivoted to the lower face of each of the blades 70 near the outer ends thereof is a rod 101, which rod is connected to rod 100 by a right and left hand turnbuckle 102, there being mating threads at the free ends 25 of said rods engaging like threads in said turnbuckle, whereby longitudinal adjustment of said rods is provided for, thereby making possible a variation of the angularity of blades 70 with respect to the posts or standards 61, in an evident manner. Medially of each of the said blades 70 is located a thumbscrew 108, adapted for frictional engagement with guide channels 105, clearly seen in Fig. 7. Two of these guide channels 30 are fixed to a bottom 2 or like element of the so-called table member B a proper distance apart to slidably engage the blades 70, as seen in Figs. 3 and 4.

To engage the table member B with the blades 70, the guides 105 or 106, as the case may be, are slipped over the blades 70 and embrace the same for their entire length, after which, pressure applied by rotating the thumb screws 108 located in said blades 45 70, against said guides, will maintain them and table member B in fixed position; to remove the latter the said thumb screws are loosened and the same slid off the blades, as easily understood.

50 The application of our invention to an automobile may now be disclosed, it being understood that the table member B has been previously engaged with the blades 70, and that said blades and all the other parts 55 such as the rods 100 and 101, the turnbuckle 102, the posts 61, nuts 77, sleeves 65 and 74, nuts 64, and bases S have been placed in assembled relationship, but not fixed in co-operative adjustment. The table member B 60 is first lifted flush with the top of the back F' of the seat F and the sloping top wall 1 of the table member B arranged to lie in a horizontal plane. The bases S are then shifted as close to the said wall F' as possible and fastened to the floor of the auto- 65

mobile by through bolts 85, the elongated surface 85^a of said bases being arranged in the line of stresses created by turnbuckles 102 as below indicated. The bases being well secured to the floor of the car, it will 70 be noted that the entire weight of the table member B is supported by them and their related parts. Now, in order to maintain the table member B non-susceptible to vibration independently of the natural vibration of the car itself, all that is necessary is to tighten nuts 74 and 75 and rotate the turnbuckles 102 in the proper direction to enforce a sufficient frictional contact of the soft buttons 10 on the table member B with 80 the back F' of the seat F in a manner readily comprehended.

While we have herein disclosed the preferred method of construction, we desire it understood that we may make such changes 85 and alterations as would suggest themselves to one skilled in the art and permitted under the doctrine of mechanical equivalents.

Having thus fully disclosed our invention we claim as new and desire to secure to ourselves by Letters Patent of the United States:—

1. An automobile luncheon table, including, in combination, a table member, supports fixed to the floor of an automobile and 95 the like, wholly and entirely supporting said table member, and crowding means in connection with said supports and table member adapted to enforce frictional contact of said table member with an adjacent 100 seat back of such automobile and the like.

2. In combination, standards, members adapted for oscillation at the upper ends thereof, adjustable members connecting said standards and oscillable members, a table 105 member superimposed on said oscillable members and connected thereto, said adjustable members being adapted to enforce frictional contact of said table member with an adjacent automobile seat back and the like, 110 and floor members adapted to be fixed to the floor of an automobile, wholly and entirely supporting said standards.

3. An automobile luncheon table, including in combination, a table member, supports having bases fixed to the floor of an automobile and the like, wholly and entirely supporting said table member, and crowding means in connection with said supports and table member adapted to enforce frictional 115 contact of said table member with an adjacent seat back of such automobile and the like, the bases of said supports being in line with the stresses created by said crowding 120 means.

4. The combination with a table member of oscillable lateral members connected to the bottom thereof, uprights supporting said lateral members, adjustable means connected to said uprights and the outer end of said 130

lateral members, whereby the upper end of
said table member may be crowded into
frictional contact with an adjacent seat back
of an automobile and the like, and floor
5 stands adapted to be fixed to the floor of
such automobile, wholly and entirely sup-
porting said uprights.

In testimony whereof we have hereunto

set our hands in the presence of two sub-
scribing witnesses.
